PARACHUTE SYSTEM

Leonard P. Frieder, Great Neck, and Walter S. Finken, Brooklyn, N. Y., assignors, by direct and mesne assignments, to Reconstruction Finance Corporation

Application June 21, 1947, Serial No. 756,190

20 Claims. (Cl. 244—138)

1

This invention relates to parachutes and in one important respect, is directed to provision for their release in a novel and sequential manner, affording parachute operation of an improved character and under conditions where it has not heretofore been deemed feasible.

This application is a continuation in part of our copending application Serial No. 669,814, filed May 15, 1946, now abandoned, for Parachutes, prosecution of said copending application having been terminated in favor of the present application wherein the claims of said copending application have been continued.

More particularly, the invention relates to parachutes and parachute systems for use under any of a variety of severe or unusual circumstances when an aerially disposed object is to be moderated in movement—referring for example to movement downward under the influence of gravity, or to other directions of motion and incipient motion where braking or retardation may be required. Thus one of many applications of the invention is in retarding and lowering safely to earth, a high speed projectile traveling at very high altitude, such as a pilotless aircraft sent far aloft for the purpose of meteorological, photographic or other observations. Other applications are in the case of loads, animate or inanimate, discharged from aircraft moving at excessive heights or at extraordinary speeds, and also exceptionally heavy loads, or those for which some delayed retardation is desired or for which a specific directional stability is sought. These are merely some examples of the character of loads wherein the advantages of the invention are most significantly realized, and numerous other examples will doubtless become apparent, in view of the following disclosure of certain illustrative embodiments. It will be understood that references herein to a load are intended, unless otherwise stated, to mean any aerially located or locatable object, body or assembly to which the movement-moderating action of a parachute is to be applied.

Important objects of the invention are to provide improved parachute operation under circumstances such as are mentioned above, and especially where parachute equipment of the sort generally available prior to our discoveries could not be employed at all, or at least with complete satisfaction. In one specific aspect, the invention involves automatic release of parachutes in response to predetermined signals or other conditions, particularly for loads so situated that there is no person available in the vicinity of

2

the load, to take control; and thus a further object is to provide new and more effective parachute-releasing arrangements.

A paramount feature of the invention resides in the controlled, sequential release of a plurality of parachutes, for a desired retarding action with a given load. As was disclosed also in our aforesaid copending application Serial No. 669,814, filed May 15, 1946, for Parachutes, there are many circumstances where a single canopy, e. g. of the usual type released manually or by a static line, cannot be safely employed; for example when the load is dropped from an aircraft traveling at very high velocity, the shock occasioned upon the opening of the parachute may well be sufficient to destroy the latter or to injure the load. We have found that this problem of high momentum loads may be overcome by providing a series of successively opened parachutes, such as one or

20 more small auxiliary canopies followed by a main or large parachute, whereby a progressive retardation takes place and there is no excessive load shock at any time. As will become further apparent in the present disclosure, there are many 25 circumstances under which two or more parachutes may be advantageously used, each connected in supporting relation to the load and effective to the desired extent for that purpose at least until a succeeding canopy is opened.

30 Further objects of the invention are to provide improvements in the retention, housing and release of parachutes; especially for the realization of automatic release and to permit a practical utilization of sequentially released parachutes under remote or otherwise unattended control.

35 To these and other ends, the invention embraces novel arrangements and instrumentalities, such as are exemplified in the annexed drawings and the following description, which are believed to afford an ample, illustrative disclosure of the broader, underlying principles.

Referring to the drawings:

Fig. 1 is a reduced, simplified view of a pilotless aircraft or projectile under the retarding effect of a small parachute provided in accordance with the invention;

Fig. 2 is a like view of the same craft, showing the structure just after a second parachute has been released and is opening up;

Fig. 3 is a further view of the craft, showing both canopies in full bloom;

Fig. 4 is a perspective view of the fuselage of the craft, with portions broken away, showing the parachute retaining structure;

Fig. 5 is a side elevation, enlarged relative to

Fig. 4, of the parts indicated in the latter, with certain covering portions broken away;

Fig. 6 is a section on line 6—6 of Fig. 5, also illustrating the parachutes in packed condition;

Fig. 7 is a section on line 7—7 of Fig. 5, showing certain control instrumentalities;

Fig. 8 is a detail view, chiefly in plan, of a timing device shown in Figs. 5 and 7;

Fig. 8a is a fragmentary section on line 8a—8a of Fig. 8;

Fig. 9 is a section corresponding to Fig. 6 but illustrating the parts just as the second parachute is being released;

Fig. 10 is a fragmentary elevation, taken from the interior of the compartment, to show parts associated with the outer door;

Fig. 11 is a wiring diagram of apparatus used with instrumentalities shown in Figs. 7 and 10;

Fig. 12 is a sectional view similar to Fig. 7, but showing a modified form of control;

Fig. 13 is a schematic view of another embodiment of the invention, showing a load under the retarding action of one of a series of parachutes to be released from structure there illustrated;

Fig. 14 shows diagrammatically the association of load and parachute pack, in this instance before the release of any parachute;

Fig. 15 is a schematic, perspective view, illustrating one manner in which the first parachute of Fig. 13 might be connected for release;

Fig. 16 illustrates an initial stage in the release and discharge of a second parachute in the device of Figs. 13 to 15;

Fig. 17 shows, somewhat diagrammatically, the relation of the several parachutes after all have been released in sequence but before the final one has fully opened;

Fig. 18 similarly illustrates the arrangement of parachutes after all have opened; and

Fig. 19 is a diagrammatic section illustrating a form of time delay device.

For the sake of illustration the apparatus of Figs. 1 to 11 inclusive is shown embodied with a jet-propelled pilotless aircraft 20 having a fuselage 21, wings 22, tail 23 and jet propulsion means 24 conveniently spaced from the parachute pack assembly which is described below. It may be assumed that this aircraft or projectile has traveled to an extremely high altitude, e. g., of the order of 50,000 feet and is progressing at a high velocity, for instance well in excess of 500 miles per hour. It may be further assumed that at a desired stage in the flight of the craft, as when its fuel is about to be exhausted or when it has reached a desired vertical or horizontal position, it should be brought to earth with safety. For example the craft may carry observational equipment which, with its records, must be retrieved, or there may be any of a variety of other reasons for recovery of the projectile.

To that end, a multiple parachute pack is disposed beneath a door 26 (Fig. 4) which originally closes an opening 27 at an upwardly and sidewardly facing portion of the fuselage 21, near the head of the craft. The pack contains a small parachute 30 having its load line 31 attached through a connector assembly 32 to a bridle 34 which may consist of a plurality of lines or cords secured to appropriately spaced positions on the fuselage 21 and extending to an apex at the connector 32, as shown. In further accordance with the invention, the small parachute is released at the desired time, for example in response to a radio signal from the ground or elsewhere and

when it opens, this canopy 30 is accompanied by no more load shock than can be properly handled, and yet it serves to retard the speed of the craft 20, e. g. as the latter begins its downward travel. Although this reduction of speed is presumably inadequate to provide a safe landing, it is nevertheless sufficient to permit safe release of a large or main parachute 40 having a load line 41 conveniently connected with that of the small parachute 30, e. g. at the connector 32. Upon final opening of the main canopy, the parts assume the positions generally indicated in Fig. 3, wherein the aircraft 20 is effectively supported by the main parachute 40 while the supplemental parachute 30 remains spread, with its axis at an angle such as shown, and with the further advantageous effect of tending to head the craft 20 into the wind as it descends. If desired, the connector 32 may comprise means (not shown) for disconnecting the load when it strikes the ground.

Bearing in mind the extreme altitude at which the initial retardation may be effected, means are also provided whereby the release of the main parachute 40 is delayed until after the first parachute has functioned as such for an appreciable time. For instance, by permitting the load 20 to fall under the moderating influence of the small parachute 30 alone for a considerable period, the total time of descent is greatly reduced and there is much less tendency toward lateral drift than if the main parachute had been opened at once; in fact, the release of the latter can be advantageously postponed until it is fully needed (say within a few thousand feet of the ground) for the desired, relatively gentle deposit of the load. For these or other purposes, a delayed control in sequential parachute release is distinctly beneficial, and in accordance with the present discoveries, the supplemental control of the second parachute (or in other cases several successive parachutes) may be effected in a variety of ways, all at least in part independent of the release and functioning of the preceding parachute; examples of instrumentalities operating in some of such ways are described below.

Referring now to the structure which carries the releasably packed parachutes, the fuselage 21 (Figs. 4, 5 and 6) encloses vertical and horizontal walls 45, 46 cooperating with the door 26 to provide a quadrant-shaped compartment having end walls 48, 49. A removable partition 50 disposed in a generally curved and sloping position between the upper end of wall 45 and the outer end of wall 46 sub-divides the space into an outer parachute compartment 51 into which the supplemental parachute 30 is packed, as in a known and appropriate manner for appropriate spreading and functioning of the canopy when released, and an inner compartment 52 containing the main parachute 40 which is similarly packed to bloom properly upon ejection. The partition 50 at its lower end has a flange 54 removably seated beneath a flange 55 that extends along inside the lower edge of the opening 27, and the upper edge 56 of the partition 50 is similarly retained by one face 57 of a large wedge-shaped longitudinal notch in a rod or shaft 58 that extends lengthwise at the top of the opening 27. The rod 58 is appropriately journaled at 59, 60 in the walls 48, 49 and has an extended shaft portion 61 on the other side of the wall 48 for purposes described below.

The door 26 may simply comprise a curved

plate, as shown, seated flush in the opening 27 against shoulders at the top and bottom and retained by a pair of lugs 63 at one end and a latch generally designated 64 at the other end (Fig. 10).

The fuselage has an opening 66 through which the bridle lines 34 extend, more or less slack, to the connector 32 and thus to the load line 31 of the packed small parachute 30. A correspondingly appropriate opening 67 is also provided for these lines in the end wall 49. Provision is likewise made for the load line 41 of the main parachute to extend around the partition 50 from the connector 32 (packed with the small parachute) to the compartment 52—for example by allowing space as shown at 69 between the end of the partition 50 and the end wall 49. For clarity of illustration Fig. 5 shows the compartment without the parachutes, except to indicate such position of the load line 41.

While a variety of signal- or other condition-responsive instrumentalities such as barometric means, speed responsive means, or means controlled by proximity of the aircraft to other objects, may be employed to effect release of the first parachute, the illustrated example shows a radio control for opening the latch 64 of the door 26. Referring to Figs. 10 and 11, the latch comprises a sliding bolt 70 held, under the tension of a coil spring 70a in engagement with a keeper 71 on the inner face of the door. The bolt carries a pin 72 sliding in a notch 73 at the end of one arm 14 of a bell crank lever pivoted to the fuselage and having its other arm 75 pivoted to the plunger-type armature 76 of a solenoid 77. Thus upon energization of the solenoid the armature 76 is attracted downwards (in Fig. 10), rocking the lever 14—75 and sliding the bolt 70 to the left so as to release the door.

By way of diagrammatic illustration and having in mind that any of a variety of radio or like controls may be provided for energization of the described electromagnetic means, Fig. 11 shows, in highly simplified form, a system comprising a radio receiver 80 feeding its signals through an amplifier 81 which is connected to energize a relay magnet 82, i. e. so that the magnet is energized when the apparatus here illustrated (and carried elsewhere on the aircraft) receives a radio signal of desired character. Upon energization of the relay magnet 82, the normally open relay contacts 83 are closed, energizing the solenoid 77 in a circuit which extends from contacts 83 through conductor 84, battery 85, conductors 86, 87 to the solenoid and back from the solenoid through conductor 89 to the contacts 83.

Upon release of the door 26, it springs out and falls clear of the aircraft; although supplemental resilient means may be provided to insure opening of the door, the packed parachute 30 will ordinarily have enough resilience for that purpose, at least to such extent that the door may be caught by the passing stream of air and thereby have itself and its lugs 63 pulled clear of the opening.

Thereupon the small parachute 30 springs or falls from the compartment 51 and opens in its intended manner, having pulled with it its load line 31 and the bridle 34. The canopy is thus deployed as shown in Fig. 1 and the main parachute 40 remains locked behind the partition 50, with its load line section 41 slack, as shown.

While any of a variety of mechanisms for actuating the release rod 58 may be provided, one simple and effective arrangement is shown for

purposes of illustration in Figs. 5, 7, 8 and 8a. The shaft extension 61 carries a cam-like element providing a radial shoulder 90 normally engaged by a detent 92 which is centrally pivoted at 93 and pivotally connected at its other end by a link 94 to one arm of a lever 95. The lever 95 is pivotally fulcrumed to a support 96, which may also carry the pivot for the detent 92, and the outer end of the lever has a slot 98 which is slidably engaged by an operating pin 99 of a rotary solenoid 100. Although other electromagnetic means may be used, the device 100, which may be of a known type, affords a relatively powerful displacement in response to energization, viz. moving the pin 99 in a clockwise direction around the center of the solenoid structure as seen in Fig. 7. A spring 102 under tension maintains the assembly in the position shown until the solenoid is energized.

The shaft portion 61 also carries a pin 104 which rests against a stationary stop 105, to prevent clockwise rotation of the shaft as seen in Fig. 7 and thus to maintain the notched rod in its proper, normal position of Fig. 6. A radial arm 106 on the shaft 61 is connected by a tensioned spring 107 to a fixed locality of the supporting structure. It will now be seen that upon energization of the solenoid, the pin 99 is moved around in the direction of the arrow, and the described levers and linkage are rocked to drop the detent 92 from engagement with the shoulder 90, whereupon the spring 107 turns the shaft 61 counterclockwise and with it the notched portion of the rod 58. As will be readily seen, this operation releases the edge 56 of the partition 52, thus releasing the main parachute 40.

While other means such as altitude-responsive (barometric) or speed-responsive or radio controlled or radio-echo actuated or like instrumentalities may be employed to release the inner parachute upon occurrence of such other types of predetermined conditions, the present structure includes a timing device 110 for actuating the solenoid 100. Such device may be of a suitable known character adapted to close a pair of contacts 112 after a predetermined time interval which may be initiated in any desired manner, for instance by the release of the small parachute 30. Thus the clock device 110 has a face 114 with a setting hand 115 that can be turned, for example manually, to a selected position and there held so that upon release its spring mechanism (not shown) will operate for a corresponding interval, moving the hand back to zero position and there closing the contacts 112. To hold the hand 115 in a selected position, there is provided a detent pin 117 slidably extending through a socket 118 at a selected portion of the face, the clock and pin socket having an appropriate cover 120 apertured so that the pin can be withdrawn at a desired time. The pin 117 is connected by a cord 122 (see also Figs. 4 and 5) to a suitable point in the assembly of the small parachute 30, e. g. to a locality on its load line 31 as illustrated in Fig. 1. Thus as the parachute 30 is released and commences to deploy, tension is applied to the line 122, withdrawing the pin 117 through the cover 120 and the corresponding aperture in an outer cover 125 over the control compartment. This action releases the hand 115, and triggers the clock mechanism so that after a predetermined number of seconds or other interval a control is effected as by closure of the

contacts 112, to energize the rotary solenoid 100 and release the main parachute 40.

The circuit for the solenoid 100 extends from the contacts 112, through conductor 127, a battery 128, conductor 129, through the solenoid and back through conductor 130 to the contacts.

Thus at the end of a predetermined time interval, which in this instance is initiated by the release of the small parachute 30, but is at the same time at least in part independently controlled (i. e. by the setting of the clock device 110), the main parachute 40 is released by unlatching its covering partition 50. If desired, a tensioned elastic cord 132 may be held in position such as shown in Fig. 6 beneath the large parachute, to facilitate ejection of the latter, release of the pressure on the cover 50 permitting the stretched cord 132 to contract as shown in Fig. 9, throwing the parachute clear for its deployment in a desired fashion. The partition 50 is ordinarily, in fact, thrown or swept clear of the aircraft at such time, thus further facilitating ejection of the large parachute.

In this fashion, the canopy 40 is thus permitted to expand as shown in Figs. 2 and 3, whereby the craft 20 is now in effect substantially entirely supported, through the tightened load line 41, by this parachute. Thus, for instance, if the timing or other control of the latter has been such as to release it within appropriate distance of the ground, it performs its function for a short but effective time, bringing the craft safely to rest.

It may sometimes become desirable to eject the main parachute simultaneously with the auxiliary canopy 30 or in effect, without regard for the functioning of the latter. For example, observation from the ground may reveal that the craft 20 is in trouble at a low altitude or should be recovered under any other circumstances where the sequential parachute operation is either unnecessary or undesirable.

To meet such emergencies the apparatus includes a supplemental relay 149 having a contact arm 141 adapted to bridge and thus close a pair of contacts 142 connected in shunt with the clock-controlled contacts 112. Referring to Fig. 11, the armature of relay 82 may carry another pair of contacts 144, insulated from the contacts 83 and normally closed until the relay is energized. A supplemental radio circuit, for instance including the receiver 145 and cooperating amplifier 146 are provided to energize a relay magnet 147 and thereby close a pair of normally open relay contacts 148; the receiver 145 is insensitive to the type of signal to which the receiver 80 responds. The contacts 148 are included in a circuit with a battery 150, that extends through the solenoid 77 and the normally closed contacts 144 of relay 82, and the winding of relay 140 is connected in shunt in the same circuit, i. e. across the series connection of solenoid 77 and contacts 144.

Thus upon receipt of a special signal which will affect receiver 145 but which, being on a different carrier frequency or otherwise of different character, will fail to actuate receiver 80, the relay magnet 147 is energized to close its contacts 148, and the contacts 144 remain closed. In consequence both the solenoid 77 and the relay magnet 140 are energized from the battery 150. Energization of the solenoid 77 opens the outer door 26 in the manner previously described, and closure of the contacts 142 by the relay 140 operates the rotary solenoid 100 and unlatches the inner partition 50, likewise as explained above. Thus

in an emergency a special signal may be sent from the ground or from an attending plane or the like, and may be selectively received at the pilotless craft, so as to release all of the parachutes, and particularly the major parachute at once. For instance if the craft 20 is observed to be falling or in trouble at a region of too low altitude to wait for the sequential operation of the two parachutes, the main parachute may be released and opened at once, for safe delivery of the load to the ground.

It will be noted that this supplemental or emergency control constitutes means responsive to a special signal or other predetermined condition whereby the main parachute can in effect be immediately released, and likewise any unreleased parachute of preceding situation in the sequence of such devices. For example if the emergency arises after the supplemental parachute 30 has been discharged but before expiration of the time provided by the device 110, the described control effectuates release of the large parachute substantially at once.

As explained above, among various kinds of control devices that may be employed for parachute release, certain specific and notably useful types are set forth herein for illustration, a further example being shown in Fig. 12. This apparatus includes, in lieu of the timing device of Fig. 7, an altitude-responsive instrumentality that comprises a barometric device generally designated 160. It will be understood that other parts of the equipment may be identical with those shown in Figs. 1 to 11, except for the timing device and its controls, and are therefore not shown again in connection with the embodiment of Fig. 12.

The barometric device 160 is disposed in the control instrument compartment and among various forms of such means that may be used, a convenient structure includes a pair of dished members 161, 162 clamped together at their flange-like peripheries to hold between them a stiff, resiliently flexible diaphragm 164. The member 161 is imperforate and thus with the diaphragm 164 constitutes a sealed chamber adapted to expand or contract in response to changes of pressure communicated to the outer side of the diaphragm through openings 165 in the member 162. An operating rod 166 extends from the center of the diaphragm to engage one arm of a lever 167, the actual engagement of the rod 166 with the lever, for instance to move it inwardly, being adjustable by appropriate means such as the screw 168 traversing the outer wall 169 of a ring or the like, carried by the rod 166. The outer end of the lever 167 transmits displacements, by a link 170, to one arm of another lever 171, and the opposite end of the lever 171 is disposed to engage a contact operating member 172 and close a pair of normally open contacts 174 upon predetermined displacement of the linked assembly of levers.

The arrangement may include parts as shown in preceding figures for turning the shaft portion 61 to release the main parachute, such means including the rotary solenoid 100 to be energized from the battery 128. The contacts 174 are connected, as shown, in series with the solenoid across the battery so that closure of the contacts energizes the solenoid and through the further mechanism, identified as in Fig. 7, permits the partition 50 to open and release the main parachute. The supplemental or emergency relay 140 may also be included as in Fig. 7 and con-

trolled as in Fig. 11, for the same purpose, viz. to release the main parachute substantially at once in response to a predetermined emergency signal or other condition. As in Fig. 7, the normally opened contacts 142 of the supplemental relay 140 are connected in shunt with the principal control contacts (contacts 174) for the rotary solenoid.

In operation, the screw 168 or other adjusting means may be preliminarily set for expected meteorological conditions, so that when the pilotless aircraft or other load has descended to a predetermined altitude, the corresponding inward displacement of the diaphragm 164 will rock the levers 167 and 171 sufficiently to close the contacts 174 and energize the relay 100. In this fashion, and assuming that the small or preliminary parachute has opened at the outset to provide its described retarding action, the main parachute is not opened until the load reaches a predetermined altitude, whereupon it is released and performs its intended function in bringing the load to the ultimately desired condition of descending travel. An arrangement of this sort is of special advantage for loads falling from extraordinary heights, since the supplemental parachute (or parachutes, if more than one such are employed) may be relied upon to sustain the load until it reaches a relatively low position, for instance an altitude of several thousand feet. Then the main parachute is automatically released and promptly moderates the descent of the load to the ultimately desired, terminal velocity.

In this fashion the total time of fall is substantially shortened and the tendency of the load to drift is very greatly reduced over a large portion of its downward path, i. e. while the small parachute alone is in operation. In consequence there is an effective stabilization of the direction in which the load travels—or in other words, much greater accuracy may be obtained in depositing the load in a predetermined locality on the surface of the earth. If desired, a light spring 176 may be associated with the assembly of levers and linkage to hold the parts in normal condition until positively displaced by movement, e. g. to the left as seen in Fig. 12, of the diaphragm 164.

By way of further example Figs. 13 to 18 inclusive illustrate another embodiment wherein a series of, say, four parachutes are to be released in desired sequence to control the descent of a load diagrammatically represented at 200. Further by way of example, it will be assumed that the load in this instance is to be discharged from a high altitude airplane or the like, so that the initial parachute of the sequence can be released under direct control on the plane, as by the usual static line.

The parachutes are releasably packed and disposed in a series of compartments 201, 202, 203 and 204 and may comprise any desired arrangement as to the relative size and ultimate disposition of their canopies, as by connection to a single or multiple load line arrangement for support of the load when released.

For instance compartments 201, 202 and 203 may respectively contain small or supplemental parachutes 205, 206 and 207 of increasing size, to be released in the stated order, and the compartment 204 may contain a main parachute 208 for final release to provide the ultimate, principal support of the load—all in accordance with the principles hereinabove explained and also as described in our cited copending application 75

Serial No. 669,814. Fig. 14 shows the assembly of packed parachutes associated with the load, it being understood that this and other aspects of the drawings are purely diagrammatic and that the actual structure will depend on factors individual to use, including the nature of the load itself.

By way of further diagrammatic illustration, Fig. 15 shows the first compartment 201, comprising a plurality of hinged or folding members 210, 211, 212, which are adapted to open out as shown in Fig. 13 for release of the parachute and which are normally held together by suitable cords 215 engaged by a releasing device 216 having a removable pin 217 connected by a cord 218 and hook 219 to a line or other support 220 in the carrying plane. It will be understood that this diagrammatically represented structure may be of any type now employed for release of a single parachute by a static line, as by pulling a pin or the like from a releasing device that retains the parachute; hence, structural details of such device are omitted from the present views.

The first parachute 205 has its individual load line 222 connected to a portion 223a of a main load line 223, the portion 223a being anchored to the load at 225. A supplemental cord 226 spliced to the line 222 carries a pin 227 releasably retained by a timing device 228 associated with the second parachute container 202. It will be understood that this timing device, which may be constructed on known principles (and may indeed be essentially of the sort embodied in Figs. 1 to 11), is triggered by withdrawal of the pin 227, as from an apertured arm 229, and after a desired period of time withdraws the arm so as to open the compartment 202. For instance, a latch cord 231 fastened to the bottom 232 of the compartment may have a ring 233 looped over the arm 229, so that when the arm is withdrawn the ring is freed and the cover 235 of the compartment may open as shown in Fig. 16. The opening of the compartment when released by the latch may be effected simply by the resilience of the packed parachute or by supplemental means such as a spring 236.

Thus upon release of the described latching parts for the compartment 202, the second parachute 206 is ejected, being retained by its own load line 237 which is connected to a further portion 223b of the main load line previously described. As the second parachute 206 moves away from the opened compartment 202, it withdraws a pin 238 from a timing device 240, which may be arranged to control a releasable latch for the third compartment 203, in the same manner as described for the compartment 202. Thus upon the end of another predetermined time interval, the compartment 203 opens in the same manner as the compartment 202, to release the parachute 207. The latter is secured by its own load line 242, which connects with a further portion 223c of the main load line that extends beyond the connecting point of the line 237 for the preceding parachute.

The parachute 207, by means of a pin 245, triggers a further timing device 246 which controls a latch for the main parachute compartment 204, for instance in a manner identical with the previously described latches. Thus after a further period of time the final compartment 204 springs open and the main parachute 208 is released, being secured to the further and final portion 223d of the main load line. If desired, release of the large parachute may be facilitated by a pilot

parachute 248 attached to its hem. Likewise, some further control may be effected by the opening of one or another of the parachutes; for instance, if it is desired to initiate operation of meteorological equipment or the like (not shown) in the load 200 when the main parachute is being deployed, a lanyard 249 may be spliced to the load line section 223d so that a pin 250 will be pulled from a suitable control device (for triggering such equipment) as the parachute is released.

It will now be appreciated that the arrangement of Figs. 13 to 18 constitutes provision for sequential release of a series of parachutes, in this instance each in a predetermined timed relation after the release of the preceding one, and after such preceding device has actually functioned as a parachute for a desired time. Thus high altitude load or a rapidly traveling or other high-momentum load may be retarded gradually until it reaches such condition of speed or altitude as is desired for operation of the main supporting parachute 208. To summarize the sequence of operations, the first parachute 205 is ejected by a static line or the like and at the outset forms the sole support for the load. After a certain time the second parachute 206 is released, and the two canopies then cooperate to constitute such support until the end of another time interval, when the third parachute 207 is released to contribute its supporting effect also, as shown in Fig. 17. After further predetermined delay the main parachute 208 is ejected and blooms—thereafter providing in the illustrated arrangement of Fig. 18, the principal load-retarding action.

As each parachute previous to the main one is ejected, a still further portion of the main load line will extend, more or less slack, from the lower end of the individual line of the last ejected parachute back to the pack assembly. In some instances, to avoid fouling or the like, it may be desirable to tie such preliminarily doubled, slack part of the main load line to the extended part by light cord which will be readily broken by the tension of the succeeding parachute when it is deployed. Thus in Fig. 17 the load line portion 223d is shown lightly tied to the junction of the load line portions 223c and 223b, at 251. As the main parachute 208 blooms fully from the condition shown in Fig. 17 the light cord at 251 is broken, permitting the line section 223d to be pulled up to the position of Fig. 18.

It will be understood that because of limitation of space in the drawings, exact representation of the linear dimensions and proportions of the several load lines is not there attempted; but persons skilled in the art will readily understand that the several lengths of line are appropriately chosen to afford the desired ultimate arrangement, e. g. as diagrammatically shown in Fig. 18. It will therein be noted that the connections of the branch lines to the main load line assembly (223a to 223d) are spaced apart by distances at least as great as the over-all lengths of the branch lines and their attached parachutes; it being further noted that the main parachute load line 41 in Fig. 3 represents a similar spacing with respect to the auxiliary parachute 30 and its line means.

For completeness of illustration, Fig. 19 shows one example of construction for timing devices such as may be used in the apparatus of Fig. 13, e. g. the timing device 228. In a suitable enclosure 255 a crosshead 256 on the arm 229 restrains a powerful, compressed, coil spring 258. The arm

229 also mounts a plunger 260 adapted to travel through a liquid-filled cylinder 261, the plunger having a very small opening 262 so that it will provide a correspondingly slow dashpot action in the cylinder. When the pin 227 is pulled, the spring urges the assembly to the right, but the retarding effect of the dashpot arrangement provides the desired time delay, i. e. in reaching the end of the stroke, where the ring 233 is freed for release of the latch constituted by it.

An advantageous feature of the use of multiple parachutes, for instance as described herein, is the effect of the several canopies in operating with their axes tilted at angles (inversely determined by their diameters) to a true vertical line, or to the line of load descent. Thus for instance where there are only two parachutes they are displaced to opposite sides of a center line; where there are a number of small parachutes and a single main parachute, the small parachutes are all displaced on the same side of a vertical line, whereas the main parachute, balancing such displacement, needs to be tilted only slightly, and in fact inappreciably, in the opposite direction, as shown in Fig. 18. It will be understood that these advantageous effects of positional relationship of the deployed canopies are obtained with arrangements of two (Fig. 3) or more (Fig. 18) parachutes arranged and connected as shown in the drawings, whether the canopies are deployed at substantially delayed times or whether they are set free together and simply deploy in sequence as their successively longer load line connections pay out and tauten.

It may be further explained that these effects are the result of several forces of reaction, i. e. exerted by the parachutes, acting on a common load or weight along the stress lines that adopt angles such as shown in Figs. 17 and 18. For example, the several auxiliary parachutes 205, 206, 207 (and indeed also the main parachute 208) produce reactionary forces on the load 200 in magnitudes substantially proportional to the square of their diameters. The force of gravity on the load is perpendicular and constant along a given axis. When this weight is acted upon by two or more forces of reaction, e. g. by the auxiliary parachutes, the line of free descent of the weight may be considered to shift laterally to a new position parallel to the original perpendicular movement. This lateral displacement, correlated with the extent of the work lines from the apex of the parachute shrouds to their anchorages, causes the several work or load lines to be disposed at angles to the perpendicular, whereby full inflation of each auxiliary parachute is achieved without hindrance from their common connecting line or other common connection. It may also be noted that the embodiment of truly hemispherical canopies in a multiple parachute arrangement according to the present invention provides a descent of more stable character than might be the case when other shapes of parachute, e. g. parabolic, are employed. It is believed that upon deployment of a second or further parachute in a series of them under the conditions described above, each hemispherical canopy will revolve on an equatorial axis, always exposing an inner surface of uniform radius to the air pressure, but with the air pressure diminishing on one side of the vertical axis while remaining constant on the other side. Under similar circumstances a canopy of parabolic form, for example, presents a non-uniform inner surface relation, with the tendency of causing the wind to

spill and of causing other improper functioning of the canopy.

Referring, for instance, to Fig. 17 it will be understood that when the first canopy 205 is opened, and before any others are released, its axis is truly vertical so as to support the load in the ordinary manner. When succeeding canopies are released, their inflation successively relieves a proportion of stress being carried by the previously deployed canopy or canopies. The proportioning of the load between or among the canopies causes each to rotate on its equatorial axis, so as to diminish the cross-sectional area represented by a vertical projection of the canopy, without decreasing the internal hemispherical area. As a result the vertical line 270 or 271 representing the center of pressure of the vertical air stream moves correspondingly to one side or other of the center line 272 or 274 of the parachute. It will be understood that a like displacement occurs in the case of a larger parachute following smaller ones, although it may not be of sufficiently appreciable extent for illustration in a drawing such as Fig. 17—reference being made, for instance, to the canopy 207 when only the three canopies 205, 206 and 207 have been deployed. In all these respects, the directions of the canopy center lines are controlled by the physical laws of force relationships and for computation purposes, are susceptible of representation by parallelograms of forces.

When the equator of a hemispherical canopy is thus tilted from the horizontal with the parachute moving in perpendicular descent the inner surface of the canopy is subject to unequal pressures relative to the true center line 272 or 274 of the parachute. As a result each canopy will be forced to move in the direction of greater pressure, e. g. the parachutes 205, 206 thus tending to move away from each other in the arrangement shown. The magnitude of this displacement is approximately governed by the sine of the angle formed by the intersection of the true center line (272 or 274) with the center line of the vertical air currents (270 or 271). Thus as previously explained, when the load 200 is suspended between the shroud apex of one parachute and that of the other (if there are only two canopies), the parachutes will tilt in opposite directions and their load lines will be spread apart at corresponding angles of tilt. As also generally explained hereinabove, similar phenomena characterize arrangements of several canopies of the sort here disclosed. In this manner the several parachutes automatically remain clear of the common or main load line, and there is no fouling of one canopy by another as they are released in sequence, nor any such fouling or blanketing during subsequent flight or descent.

In practice these systems of plural canopies may likewise be of advantage, under at least certain wind conditions, to permit or facilitate the landing of the load in a definite position relative to the wind direction. For example, if the horizontal wind velocity is greater than the descending velocity, and also in some cases (e. g. of long distances of descent) where the horizontal wind velocity is somewhat less, the small or auxiliary parachutes will all fly with the wind, i. e. be positioned to leeward, so that the load will tend to land with a predetermined heading into the wind. For the last mentioned purpose, it will be understood that the load should be suitably connected, e. g. to prevent or impede its turning about a vertical axis relative to the angular position of the

parachutes about such axis. As stated above, it is believed that in these and various other respects distinctly preferred results are obtained when the invention is embodied with parachutes having hemispherical canopies.

It will now be seen that the present invention affords improved parachute arrangements, which are of special utility under a wide variety of circumstances and which involve a novel and sequential release of the parachutes. The control may be automatic to whatever extent is desired and may be effected in a variety of ways and in response to the occurrence of a variety of conditions, e. g. the passage of time, the receipt of a predetermined signal, the existence of a predetermined physical circumstance of the load, or the like.

It is to be understood that the invention is not limited to the specific embodiments herein shown and described but may be carried out in other ways without departure from its spirit as defined by the following claims.

We claim:

1. Parachute apparatus comprising, in combination, a plurality of releasably packed parachute assemblies to be associated with a load for sequential release of the parachutes, each of said parachute assemblies comprising a canopy and load-supporting line means which include shroud means beneath the canopy and which extend from the canopy toward the load, means for connecting the lower ends of the load-supporting line means of the parachute assemblies to a common, unitary load and in direct supporting relation of each parachute assembly therewith, a first parachute assembly and an immediately subsequent parachute assembly, of said sequence, being releasable to deploy at successively more remote localities from the load, the line means of said subsequent parachute assembly comprising a load line which extends from its shroud means to the lower end of said line means, said load line being longer than the aforesaid line means of said first parachute assembly, said first parachute assembly being disposed wholly at one side of and free of the said subsequent parachute assembly at all localities above said connecting means when said parachutes are released, and means for releasing said parachutes in desired sequence, including means responsive to occurrence of a predetermined condition at a determinable time subsequent to deployment of said first parachute, for releasing said subsequent parachute.

2. Parachute apparatus as described in claim 1, wherein the last-mentioned means comprises a timing device controlled by a previous parachute in accordance with release thereof, for releasing said subsequent parachute in response to occurrence of a predetermined period of delay.

3. Parachute apparatus as described in claim 1, wherein the last-mentioned means comprises an altitude-responsive device for releasing said subsequent parachute at a predetermined positional condition of the load.

4. Parachute apparatus as described in claim 1, wherein the parachute releasing means includes means responsive to a predetermined signal traveling thereto from a locality remotely and aerially spaced from the load, for releasing the first parachute.

5. Parachute apparatus as described in claim 1, wherein the last mentioned means is adapted to be delayed in its operation for releasing said subsequent parachute, until after a preceding parachute of the sequence has been released and has

functioned as a parachute for at least an appreciable time, and wherein the releasing means also includes emergency means responsive at any time to another predetermined condition for immediately and substantially simultaneously releasing said subsequent parachute and any unreleased parachute of preceding situation in the sequence.

6. Parachute apparatus as described in claim 1, wherein the parachute releasing means includes means responsive to a predetermined signal of radiant energy, for releasing said first parachute and also includes emergency means responsive at any time to another predetermined signal of radiant energy, for immediately and substantially simultaneously releasing said subsequent parachute and any unreleased parachute of preceding situation in the sequence.

7. Parachute apparatus for moderating the movement of a load to reach a predetermined ultimate condition of descending travel, comprising, in combination, a plurality of releasably packed and sequentially releasable parachutes adapted for association together with a load for support thereof when released, a first one of said parachutes having a minor retarding effect and a subsequent one of said parachutes having movement-retarding effect substantially greater than the first and sufficient to provide said predetermined ultimate condition, means for releasing said parachutes in desired sequence, including means responsive to occurrence of a predetermined condition for releasing said subsequent parachute, compartment structure for holding the parachutes and having an opening through which the parachutes are to be released, and a movable partition separating an inner chamber of said compartment from said opening and having a releasable fastening, said first parachute being disposed on the outer side of said partition and said subsequent parachute being disposed in said inner chamber, and said condition-responsive means comprising means for releasing the fastening of said partition.

8. Parachute apparatus comprising, in combination, a first parachute assembly comprising a canopy and load-supporting line means including shroud means extending from the canopy to a point beneath it and a load line extending down from said point toward the load, a second parachute assembly comprising a canopy and load-supporting line means which include shroud means beneath the canopy and which extend down from the canopy toward the load, and means for connecting the lower end of the load line of the first parachute assembly and the lower end of the load-supporting line means of the second parachute assembly to a common, unitary load and in direct supporting relation of each parachute assembly therewith, said load line of the first parachute assembly being longer than the load-supporting line means of the second parachute assembly so that said first canopy and its shroud means may deploy above the second canopy, and said second parachute assembly being disposed wholly at one side of and free of the first parachute assembly at all localities above the aforesaid connecting means, so that each parachute assembly may deploy separately from and clear of the other and in direct supporting relation to the load.

9. Parachute apparatus comprising, in combination, a first parachute assembly comprising a hemispherical canopy and load-supporting line means including shroud means extending from

the canopy to a point beneath it and a load line extending down from said point toward the load, a second parachute assembly comprising a hemispherical canopy and load-supporting line means which include shroud means beneath the canopy and which extend down from the canopy toward the load, and means for connecting the lower end of the load line of the first parachute assembly and the lower end of the load-supporting line means of the second parachute assembly to a common, unitary load and in direct supporting relation of each parachute assembly therewith, said load line of the first parachute assembly being longer than the load-supporting line means of the second parachute assembly so that said first canopy and its shroud means may deploy above the second canopy, and said second parachute assembly being disposed wholly at one side of and free of the first parachute assembly at all localities above the aforesaid connecting means, so that each parachute assembly may deploy separately from and clear of the other and in direct supporting relation to the load.

10. An apparatus of the character described comprising a main parachute, a load line connecting the load to said main parachute, a plurality of branch lines extending from said load line, a secondary parachute on the end of each of said branch lines, said branch lines being spaced apart along the load line by distances greater than the lengths of the branch lines and said secondary parachutes being graduated in size to decelerate the load before the main parachute is fully deployed.

11. An apparatus of the character described comprising a main parachute, a load line connecting the load to said main parachute, a plurality of branch lines extending from said load line, a secondary parachute on the end of each of said branch lines, said branch lines being spaced apart along the load line by distances greater than the lengths of the branch lines and said secondary parachutes being graduated in size to decelerate the load before the main parachute is fully deployed, each of said main and secondary parachutes having a hemispherical canopy.

12. An apparatus of the character described comprising a load line attached at one end to the load, a plurality of branch lines extending from the load line and spaced apart distances at least as great as the lengths of the branch line, a parachute attached to the end of each branch line and another parachute attached to the end of the load line, the parachute nearest the load being the smallest and the parachute on the end of the load line being the largest of the plurality of parachutes.

13. An apparatus of the character described comprising a main parachute, a smaller parachute, a long line connecting the main parachute to the load, and a shorter line connecting the smaller parachute to the load whereby when the main parachute and the load are launched at substantially the same time the smaller parachute will decelerate the load before the long line is tensioned to transfer control of the load to the main parachute, said main parachute having a canopy and shroud means therefor converging to a point under the canopy, said shroud means being attached at said point to said long line, said smaller parachute comprising a canopy and shroud means therefor, the aforesaid point being disposed at a distance from the load on said long line which is greater than the over-all length between the smaller parachute canopy

and the load, measured along the assembly constituted by said smaller parachute and the shorter line, and said smaller parachute canopy and its shroud means being disposed at one side of the long line so that said smaller canopy and its shroud means may deploy clear of the long line at one side thereof.

14. An apparatus of the character described comprising a main parachute, a smaller parachute, a long line connecting the main parachute to the load, and a shorter line connecting the smaller parachute to the load, said main parachute having a canopy and shroud means therefor converging to a point under the canopy, said shroud means being attached at said point to said long line, said smaller parachute comprising a canopy and shroud means therefor, the aforesaid point being disposed at a distance from the load on said long line which is greater than the over-all length between the smaller parachute canopy and the load, measured along the assembly constituted by said smaller parachute and the shorter line, and said smaller parachute canopy and its shroud means being disposed at one side of the long line so that said smaller canopy and its shroud means may deploy clear of the long line at one side thereof, said parachutes and lines being releasably packed, means for releasing the smaller parachute, and means for releasing the main parachute at a determinable time after the smaller parachute has been released, said last mentioned means including a control device therefor, controllable independently of the release of said smaller parachute, for determining said time.

15. An apparatus of the character described comprising a main parachute, a smaller parachute, a long line connecting the main parachute to the load, and a shorter line connecting the smaller parachute to the load, said main parachute having a hemispherical canopy and shroud means therefor converging to a point under the canopy, said shroud means being attached at said point to said long line, said smaller parachute comprising a hemispherical canopy and shroud means therefor, the aforesaid point being disposed at a distance from the load on said long line which is greater than the over-all length between the smaller parachute canopy and the load, measured along the assembly constituted by said smaller parachute and the shorter line, and said smaller parachute canopy and its shroud means being disposed at one side of the long line so that said smaller canopy and its shroud means may deploy clear of the long line at one side thereof.

16. An apparatus of the character described comprising a main parachute having a canopy and including shroud lines therefor converging to an apex below the canopy, a load line connecting the load to said main parachute, said load line extending to the load from the said apex of the shroud lines of the main parachute, a branch line extending from a point on the load line, and a parachute smaller than the main parachute on the end of said branch, said load line having a length between said point and the aforesaid apex greater than the over-all length of the assembly constituted by the branch line and its attached smaller parachute, and said last-mentioned assembly being disposed wholly at one side of and free of the load line at all localities above said point.

17. Parachute apparatus comprising, in combination, a releasably packed main parachute having a canopy and including shroud lines there-

for converging to an apex below the canopy, a load line connecting the load to said main parachute, said load line extending to the load from the said apex of the shroud lines of the main parachute, a branch line extending from a point on the load line, and a releasably packed parachute smaller than the main parachute on the end of said branch, said load line having a length between said point and the aforesaid apex greater than the over-all length of the assembly constituted by the branch line and its attached smaller parachute, and said last-mentioned assembly being disposed wholly at one side of and free of the load line at all localities above said point when said parachutes are released, and means for sequentially releasing the parachutes, including means for releasing the main parachute at a determinable time after the smaller parachute has been released, said last mentioned means including a control device therefor, controllable independently of the release of said main parachute, for determining said time.

18. Parachute apparatus comprising, in combination, a main parachute having a canopy and including shroud lines therefor converging to an apex below the canopy, a load line connecting the load to said main parachute, said load line extending to the load from the said apex of the shroud lines of the main parachute, a branch line extending from a point on the load line, and a secondary parachute on the end of said branch, said load line having a length between said point and the aforesaid apex greater than the over-all length of the assembly constituted by the branch line and its attached secondary parachute, and said last-mentioned assembly being disposed wholly at one side of and free of the load line at all localities above said point when said parachutes are released, said parachutes and lines being releasably packed, and means for releasing said secondary and main parachutes in sequence, including a timing device controlled by the secondary parachute and set in operation by release thereof, and means controlled by the timing device to release the main parachute upon lapse of a predetermined time following release of said secondary parachute.

19. Parachute apparatus comprising, in combination, a main parachute having a canopy and including shroud lines therefor converging to an apex below the canopy, a load line connecting the load to said main parachute, said load line extending to the load from the said apex of the shroud lines of the main parachute, a branch line extending from a point on the load line, and a secondary parachute on the end of said branch, said load line having a length between said point and the aforesaid apex greater than the over-all length of the assembly constituted by the branch line and its attached secondary parachute, and said last-mentioned assembly being disposed wholly at one side of and free of the load line at all localities above said point when said parachutes are released, said parachutes and lines being releasably packed, and releasing devices for the parachutes and control means responsive to change in altitude of the load, for operating the releasing device of the main parachute, after the secondary parachute has been released.

20. A parachute apparatus comprising a load line having the load attached to one of its ends and a main parachute attached to the other end, and a secondary parachute connected to the load line at a point intermediate the load and the main parachute, the apparatus being operated by

launching the load and thereby rendering the secondary parachute effective to retard the load before the main parachute opens, said parachutes and load line being connected and arranged with the load so that only after the secondary parachute has deployed and while it is acting in supporting relation to the load, the main parachute then deploys under the tension of the load on the load line and above the secondary parachute, each of said parachutes comprising a canopy and shroud lines converging beneath the canopy, the end of the load line which is attached to the main parachute being connected to the lower end of the shroud lines thereof, the said load line having a length between its said last-mentioned end and the aforesaid intermediate point, which is greater than the over-all length between the top of the canopy of the secondary parachute and the said intermediate point, and the said secondary parachute having its canopy and shroud lines disposed wholly at one side of and free of the said load line.
